Walter G. Hanchuk(57) **CLAIM**

The ornamental design for container with label, as shown and described.

DESCRIPTION

FIG. 1 provides a top, front perspective view of a container with label showing my new design in a closed or sealed position;

FIG. 2 provides an above view thereof;

FIG. 3 provides a below view thereof;

FIG. 4 provides a front view thereof;

FIG. 5 provides a rear view thereof; and,

FIG. 6 provides a top, front perspective view of the container with label of FIG. 1, shown in a partially open or unsealed position.

The unshaded area within the evenly dashed broken lines in FIG. 6 illustrates the portion of the design that forms no part of the claim.
